UNITED STATES PATENT OFFICE.

GEORGE HOLLOWAY, OF CHARTHAM, NEAR CANTERBURY, ENGLAND.

PAPER-MAKING MACHINERY.

SPECIFICATION forming part of Letters Patent No. 231,169, dated August 17, 1880.

Application filed July 13, 1880. (No model.) Patented in England January 5, 1876.

To all whom it may concern:

Be it known that I, GEORGE HOLLOWAY, of Chartham, near Canterbury, in the county of Kent, in England, have invented certain 5 new and useful Improvements in Paper-Making Machines, of which the following is a specification.

My invention pertains to Fourdrinier paper-machines, and applies particularly to the location of the slices which control the flow of the pulp to the wire, to the arrangement of the apron whereby no adjustment of it is required when changes in width of paper are to be made, and to the arrangement of the deckles 15 and their accessories.

By a combination of the improvements superior paper is produced, and no stoppage of the machine need occur as widths are changed.

In the accompanying drawings, Figure 1 is 20 a side elevation of a Fourdrinier paper-forming machine with my improvements attached. Fig. 2 is a vertical longitudinal section of the receiving-trough and its immediate accessories; Fig. 3, a perspective view, part longitudinal 25 vertical section, of the parts in the immediate neighborhood of the receiving-trough; Fig. 4, an elevation of the forward or second slice, E; and Fig. 5, an elevation of the packing-piece S, which prevents the side flow of pulp at 30 the breast-roll, together with some of its adjuncts.

A is the breast-roll, and C the receiving-trough. The front of the receiving-trough is provided with a flow-lip, W, whose edge forms 35 a clamp, I. In this clamp is held the apron Q, which is of thin doubled sheet-rubber or other suitable material. This apron projects a quarter of an inch or so, and bears nicely on the breast-roll A, or upon the wire, rather, upon 40 the breast-roll. Fig. 5 shows these parts plainly. The lip and the apron extend from end to end of the receiving-trough, and are never disturbed when altering the width of paper. The apron will need renewal about as often 45 as the wire does.

As shown in Fig. 2, two slices, D and E, are placed in the receiving-trough C, one of them, E, being very near the flow-lip apron. These slices control the flow of pulp to the 50 wire, and the usual slices forward of the breast-roll are dispensed with. This avoids the dis-

turbance of the pulp after it has reached the wire, and allows a superior quality of paper to be made. The two slices D and E are adjustable vertically, as usual, by set-screws or any 55 suitable means; and in practice I prefer to provide the forward slice, E, with means for adjusting different portions of its edge independently. This allows natural sag to be corrected, and gives complete control of the whole 60 length of its edge.

In order to effect this adjustment of the edge of this slice, I provide the body of the slice with a blade, f, as shown in Figs. 2 and 4, fixed to the body of the slice at each end, as at l in 65 Fig. 4, and supported intermediately by screws d. These screws, being properly adjusted, cause the blade f to be flexed vertically at any point and to any proper degree required. To render the blade f more flexible vertically, 70 notches i are cut in its upper edge to weaken it.

In all of the figures where shown, L is one of the deckle-frames for supporting the deckle-pulley, &c. These frames are to be provided with any usual or suitable means for adjusting them sidewise in altering the width of 75 paper.

F is a head deckle-pulley; B, a deckle-strap; P, the table-rolls; N, the save-all, and O a scraper bearing upon the breast-roll A and 80 draining into the save-all. The scraper O is removable, being attached to the edge of the save-all, and by its location is rendered self-washing.

As shown in Fig. 3, the deckle-frame L has 85 attached to its end an elbow-piece, G. This elbow is bolted to the frame at M, and after reaching around the pulley F, &c., its long arm takes a bottom bearing tightly against the flow-lip W, being held down snugly by 90 the spring H, or by any other suitable means. The face of the long arm of the elbow bears nicely against the end V of the receiving-trough C, being pressed snugly by the spring K. The joint-surfaces of the elbow-piece G 95 may be padded to insure water-tight fits. The elbow G is seen to form a part of the deckle-frame L, and to be capable of moving with the deckle-frame as the latter is adjusted for different widths of paper. The elbow-pieces form the water-tight front of the receiving-trough and allow the passage of pulp 100

to the wire only through the regular channel between the deckles and elbows.

After the top of the breast-roll is reached by the pulp the deckle-straps, of course, prevent 5 improper side flow; but between the top of the breast-roll and the apron Q there are points where side flow may occur, and it becomes imperative that means be provided for closing all side passages between the points named. This 10 I accomplish by causing the short arm U of the elbow-piece to make a close joint on the wire from the front of the lip W to the point at the top of the breast-roll, where the deckle-strap becomes effective.

15 The long arm G of the elbow-piece makes a close bottom joint with the flow-lip, as previously mentioned and as shown in Fig. 5.

From the edge of the flow-lip to the edge of the apron Q side flow is prevented by the cushioned block J, whose bottom rests delicately upon the apron. This block may be affixed to the elbow in any suitable manner. From the edge of the apron to the point where the deckle-strap becomes effective side flow is prevented 20 by the block S, which fits the wire neatly. The forward end of this block is thin and delicate, and is lightly pressed against the deckle-strap by the spring T.

The block S is best made of gutta-percha or 30 some similar substance. As the block S is subject to wear at its lower edge, it should be provided with means for vertical adjustment.

In practice I render the block S self-adjustable vertically by affixing a weight, R, to it 35 and fitting the weight to slide in a mortise in the elbow-piece. By this plan a self-adjusting water-tight joint is formed at all required points.

The blocks J and S may, of course, be in one 40 piece, and may be said to form a packing for the short arm of the elbow, and the short arm of the elbow may, in fact, form the blocks or their substitute; but in practice I find the construction specified to be the most perfect.

45 The whole of the elbow-piece and its accessories are rendered more adaptable if pivoted at M, instead of rigidly bolted.

My improvements have been practically tested in the every-day work of the paper-mill, 50 and it is found that owing to manner of slic-

ing the flowing pulp a superior quality of paper is produced, and that hourly alterations in the width of paper being made involve no stoppage or trouble.

I claim as my invention—

1. The combination, with the receiving-trough, of two slices arranged within the trough and adapted to control the flow of pulp to the wire, substantially as set forth. 55

2. The combination, with the body of a slice, 60 of a vertical flexible blade attached to the body of the slice at each end and provided with one or more intermediate adjusting-screws, substantially as set forth.

3. The combination, with a breast-roll and 65 a receiving-trough, of a narrow soft edge or apron attached the full length to the flow-lip of the receiving-trough, and adapted to operate substantially as set forth.

4. The combination, with a deckle-frame, a 70 breast-roll, and a receiving-trough, of an elbow-extension of the deckle-frame, adapted to fit and form a water-tight joint upon the wire, upon the flow-lip of the receiving-trough, and against the end of the receiving-trough, and arranged to operate substantially as set forth. 75

5. The combination, with an elbow-extension of a deckle-frame adapted to prevent undesired side flow of pulp, of a packing-block adapted to fit upon and adjust itself vertically upon the 80 wire, substantially as set forth.

6. The combination, with a deckle-strap and a block adapted to fit the wire and prevent improper side flow of pulp, of a spring arranged to press upon and hold said block, or a portion 85 of it, against the deckle-strap, substantially as set forth.

7. The combination, with a deckle-frame and a receiving-trough, of an elbow-extension of the deckle-frame, a spring to press said elbow-extension downward upon the receiving-trough, and a spring to press said elbow-extension against the end of the receiving-trough, 90 substantially as set forth.

GEORGE HOLLOWAY.
